UNITED STATES PATENT OFFICE

124,913

DESIGN FOR A SHOE

George H. Bingham, Jr., Cambridge, Mass.

Application November 18, 1940, Serial No. 96,650

Term of patent 3½ years

To all whom it may concern:

Be it known that I, George H. Bingham, Jr., a citizen of the United States, residing at Cambridge, in the county of Middlesex and Commonwealth of Massachusetts, have invented a new, original, and ornamental Design for a Shoe, of which the following is a specification, reference being had to the accompanying drawing, forming a part thereof, in which

Figure 1 is a side elevation of a shoe showing my new design;

Figure 2 is a rear end view of the shoe shown in Figure 1; and

Figure 3 is a perspective view of the shoe shown in Figure 1.

My design is characterized by a covering material which is slotted diagonally, as shown, the portions of the surfaces exposed by the slots having an appearance contrasting with that of the covering material itself.

I claim:

The ornamental design for a shoe, substantially as shown and described.

GEORGE H. BINGHAM, JR.
